CLAIM

The ornamental design for set of grips for an exercise bar, as shown and described.

DESCRIPTION

FIG. 1 is a perspective view looking upwardly at the front, bottom and right side of a set of grips for an exercise bar; FIG. 2 is a front elevation thereof;

FIG. 3 is a rear elevation thereof;

FIG. 4 is a left side elevation of the left hand grip of the set of grips for an exercise bar;

FIG. 5 is a right side elevation of the left hand grip;

FIG. 6 is a left side elevation of the right hand grip of the set of grips for an exercise bar;

FIG. 7 is a right side elevation of the right hand grip;

FIG. 8 is a top view of the set of grips for an exercise bar;

FIG. 9 is a bottom view of the set of grips for an exercise bar; FIG. 10 is a front view of the set of grips for an exercise bar in position on an exercise bar, which is shown in broken lines to illustrate the environment of the claimed design and forms no part thereof;

FIG. 11 is a perspective view looking upwardly at the front, bottom and right side of a second embodiment of a set of grips for an exercise bar;

FIG. 12 is a front elevation thereof;

FIG. 13 is a rear elevation thereof;

FIG. 14 is a left side elevation of the left hand grip of the set of grips for an exercise bar;

FIG. 15 is a right side elevation of the left hand grip;

FIG. 16 is a left side elevation of the right hand grip of the set of grips for an exercise bar;

FIG. 17 is a right side elevation of the right hand grip;

FIG. 18 is a top view of the set of grips for an exercise bar;

FIG. 19 is a bottom view of the set of grips for an exercise bar; and,

FIG. 20 is a front view of the set of grips for an exercise bar in position on an exercise bar, which is shown in broken lines to illustrate the environment of the claimed design and forms no part thereof.

The broken lines in the drawings illustrate environmental structure which forms no part of the claimed design.
